PORTRABLE ROAD SIGNAL

John H. Hagood, Ross C. Albert, and William W. Moss,
Birmingham, Ala.

Application February 11, 1955, Serial No. 34,486

Term of patent 14 years

(Cl. D72—1)

Fig. 4

Fig. 5

Fig. 3

Fig. 1 is a perspective view of a portable road signal showing our new design, the same being shown in unfolded position;

Fig. 2 is a side elevational view thereof;

Fig. 3 is a top plan view thereof;

Fig. 4 is a front elevational view thereof; and,

Fig. 5 is a rear elevational view thereof.

What we claim is:

The ornamental design for a portable road signal, as shown.
